UNITED STATES PATENT OFFICE.

REGINALD G. STANDERWICK, OF LYNN, MASSACHUSETTS, ASSIGNOR TO GENERAL ELECTRIC COMPANY, A CORPORATION OF NEW YORK.

HEADLIGHT.

1,157,966.

Specification of Letters Patent. Patented Oct. 26, 1915.

Application filed June 3, 1915. Serial No. 31,844.

To all whom it may concern:

Be it known that I, REGINALD G. STANDERWICK, a subject of the King of Great Britain, residing at Lynn, in the county of Essex, State of Massachusetts, have invented 5 sex, certain new and useful Improvements in Headlights, of which the following is a specification.

My invention has reference to a headlight, 10 and especially to a headlight using an incandescent lamp as the source of light, and more particularly relates to a simple and convenient support for the lamp by which the light source is universally adjustable 15 with reference to the reflector with which the same is used, and by which the same may easily be secured in its adjusted position by a single clamping operation.

When it is desired, by means of a parabolic reflector, to provide a beam of parallel rays from a source of artificial light, it is, of course, important that the light source should, as nearly as possible, coincide with the focus of the parabolic reflector, since any slight displacement therefrom, such as is likely to result in practice from the rather severe shocks which the headlight receives from the locomotive or other vehicle on which the same is used, seriously impairs 30 the light beam, and this effect is especially pronounced where a lamp provided with a concentrated filament, such, for example, as is disclosed in an application for Letters Patent which was filed on or about November 28th, 1913, by M. J. Mackay, Serial No. 861,279, is used. My invention provides 35 means by which the operator may readily bring the filament of the lamp to the focus of the reflector and secure the same in its 40 adjusted position.

For a fuller understanding of my invention, reference may be had to the accompanying drawings, in which—

Figure 1 is a vertical section of a device 45 embodying one form of my invention; Fig. 2 is a plan view of the lower portion of the ball socket and of the split ball engaging the same; and Fig. 3 is a longitudinal section showing a modified form of my invention.

The form of my invention shown in Fig. 50 1 is applicable to any headlight, and may readily be applied to headlights already in use. A part of the casing is represented by the numeral 10, and upon this casing is 55 mounted a base support 11 provided with

suitable flanges, by which the same is secured to the casing, and with a transverse opening 12. The base support is also provided with registering openings 13 in the portions above and below the opening 12. 60 The lower opening is provided with screw threads at 14, and is adapted to receive a screw-threaded thimble 15, provided at its enlarged upper end with teeth 16 by which the same may be turned and the thimble adjusted longitudinally. The upper end of the thimble is formed with a spherical recess 17 which, together with a similar recess 18 in the upper portion of the base support, and formed as a continuation of the opening 13, forms a ball socket for the reception of a split clamping member, here shown as a ball, 19, preferably formed of two sections 19^a and 19^b, which are here shown as separate. It will be understood, however, that any other equivalent form of split ball may be used. It is, of course, unnecessary that the entire ball should be spherical in form, as it is only necessary that those portions should be spherical which are received in 80 the socket. A hollow lamp standard 20 passes through an opening in the ball 19 and through an opening 22 in the reflector 21, so as to bring the light source, which is here shown as an incandescent lamp, in the 85 focus of the parabolic reflector. The conductors 24 for the incandescent lamp pass through an opening 25 in the lamp standard, and are carried through the standard to the lamp. Screws 26 and 27, tapped into the 90 base support 11 and into the lamp standard 20, respectively, project, one with its shank and the other with its head, into the spaces between the two sections 19^a and 19^b of the ball, and thus prevent rotation of the ball 95 with respect to the base support, and thus injury by the twisting of the conductors is avoided. It will be understood, however, that both screws may engage the same space at one side of the lamp standard 20, and in 100 Fig. 3 this construction is illustrated.

The manipulation of the lamp support illustrated in Fig. 1 is as follows: When it is necessary to focus the incandescent lamp, the thimble 15 is moved longitudinally 105 away from the ball, preferably by means of a suitable wrench which engages the teeth 16. This movement of the thimble loosens the ball in its socket, and at the same time permits rotation thereof in any direction, 110

and also permits longitudinal movement of the lamp standard 20 therethrough. The incandescent lamp is thus given a universal movement with reference to the reflector, 5 and may be brought into the exact focus thereof, and the operator may conveniently retain the same in this position with one hand while he again moves the thimble 15 longitudinally until the ball and the stand- 10 ard are locked in position with the source of light at the focus of the reflector. It will, of course, be understood that the opening 13 in the upper portion of the base support and the opening through the thimble 15 15 are sufficiently large to permit of the necessary rotation of the ball within its socket.

In Fig. 3, I have shown a modification of my invention, in which the base support is applied to the back of the headlight casing, 20 and the thimble which clamps the ball in position extends without the casing, and is rotatable by a suitable handle without the casing. In this form of my invention, the support 11 is provided with a contracted 25 portion 11^a, the rear end of which extends through an opening 10^a in the casing 19, to which the base support is secured by screws or other suitable means. The thimble 15^a is provided with a hand-wheel 16^a located 30 without the headlight casing. The lamp support 20 also extends without the casing, so that the light may be readily adjusted from the exterior of the headlight.

In accordance with the provisions of the 35 patent statutes, I have described the principle of operation of my invention, together with the apparatus which I now consider to represent the best embodiment thereof; but I desire to have it understood that the apparatus shown is only illustrative, and that the 40 invention can be carried out by other means.

What I claim as new, and desire to secure by Letters Patent of the United States, is:—

1. A lamp support for a headlight comprising a split clamping member, a lamp standard passing through said member, and

a movable member provided with a recess for receiving the clamp, the recess being so formed as to close the clamp when the member in which it is located is shoved longitudinally. 50

2. A lamp support for a headlight comprising a perforated base support, a screw-threaded member received in said support and forming therewith a ball socket, a split ball adapted to be received in said socket, and a lamp standard passing through and longitudinally movable in said ball. 55

3. In a headlight, a perforated base support, a screw-threaded member received in 60 said support and forming therewith a ball socket, a split ball received in said socket, a parabolic reflector provided with a side opening, and a lamp standard passing through and longitudinally movable in said 65 ball and extending through the opening of said reflector.

4. A lamp support for a headlight comprising a perforated base support, a screw-threaded member received in said support 70 and forming therewith a ball socket, a split ball adapted to be received in said socket, a hollow lamp standard passing through and longitudinally movable in said ball and adapted to carry the conductors to the light 75 on said standard, and means for preventing rotation of said ball with reference to said standard.

5. In a headlight, a casing, a base support mounted upon said casing, a screw-threaded 80 member received in said support and forming therewith a ball socket, said member extending without the casing of the headlight, a split ball received in said socket, and a lamp standard passing through and longitudinally movable in said ball and extending 85 through said member, whereby the light is adjustable without the casing of the headlight.

In witness whereof I have hereunto set my 90 hand this first day of June, 1915.

REGINALD G. STANDERWICK.
